[57] CLAIM

The ornamental design for a dual compartment cooler, as shown and described.

DESCRIPTION

FIG. 1 is a perspective view of a dual compartment cooler showing my new design with the lid open;

FIG. 2 is a top plan view thereof;

FIG. 3 is a bottom plan view thereof;

FIG. 4 is a left side elevational view thereof, the opposite side being identical;

FIG. 5 is a rear elevational view thereof;

FIG. 6 is a front elevational view thereof; and

FIG. 7 is a cross-sectional view thereof taken along line 7—7 of FIG. 2.

FIGS. 2-7 are shown with the lid in a closed position for ease of illustration.

FIG. 2

FIG. 1

FIG. 4

FIG. 3

FIG. 6

FIG. 5

FIG. 7
